(57) **CLAIM**

The ornamental design for a medical equipment cart as shown and described.

DESCRIPTION

FIG. 1 is a front elevation view of a medical equipment cart showing our new design;

FIG. 2 is a left side elevation view;

FIG. 3 is a right side elevation view;

FIG. 4 is a rear elevation view;

FIG. 5 is a top plan view;

FIG. 6 is a bottom plan view;

FIG. 7 is a perspective view; and,

FIG. 8 is another perspective view.

Any broken lines in FIGS. 1-8 illustrate unclaimed portions of the medical equipment cart and form no part of the claimed design.

1 Claim, 8 Drawing Sheets
